UNITED STATES PATENT OFFICE.

OTTO BECKER, OF BERLIN-HENNIGSDORF, GERMANY, ASSIGNOR TO PORZELLAN-FABRIK PH. ROSENTHAL & CO. A.-G., OF BERLIN, GERMANY.

ELECTRIC SUSPENSION INSULATOR.

Application filed July 31, 1924, Serial No. 729,361, and in Germany May 2, 1923.

This invention relates to electric suspension insulators of the type, in which the insulator is provided with a cap, and has for its object to provide a connection between the cap and 5 the body of the insulator without the employment of cement.

It has already been proposed to provide grooves in the cap and in the body of the insulator and to insert into these grooves 10 through openings in the wall of the cap a wire or other flexible member, which lies in the grooves in the body of the insulator and the cap, whereby the parts are keyed together. It has also been proposed to screw intermediate pieces into the cap from below through 15 openings, which by a wedging action form a connection between the cap and the bolt.

This known type has the disadvantage that the grooves make the wall of the insulator uneven and that the manufacture is difficult. There are also considerable stresses spread over relatively small areas, as the inserted wire must not have too great a diameter and the retaining function of the wire is exerted 25 only on a quarter of its periphery at the most.

The employment of the inserted retaining pieces entails that, owing to the necessity of leaving bridges between the insertion openings, the retaining pieces do not grip the body 30 of the insulator over its entire periphery, but only over a portion of the same. While retaining pieces screwed in from below do not have this disadvantage, they necessitate making a thread in the cap and in the retaining 35 pieces and therefore make the manufacture of the cap and the retaining pieces relatively costly.

The present invention obviates this disadvantage and consists in a combination of these 40 known or previously proposed constructional forms and is characterized in this that retaining pieces having a wedge-like action or an inclined abutment surface facing the body of the insulator are inserted from below into 45 the cap and are connected to the cap by a member, which engages grooves in the retaining pieces and in the cap. These grooves require no special tooling, while the abutment surface of the retaining pieces may 50 either be tooled or may abut without any tooling against yielding insertions placed against the insulator body.

The accompanying drawing shows a constructional example of the invention, Figure

1 being a section through the insulator body, 55 the cap and the retaining pieces and Figure 2 a plan view of the retaining pieces.

The body A of the insulator is provided with inclined abutment surfaces, against which the retaining pieces D rest. These 60 may be wedge-shaped in cross-section and be provided with one or more grooves, opposite which are one or more grooves J in the cap B. Into these oppositely located grooves a member O is inserted, which preferably fills the 65 entire cross-section formed by opposite grooves and may be a piece of wire or the like. The member O is inserted from outside in a known manner through one or more openings Z in the wall of the cap. These openings may 70 be subsequently closed, but this does not form a feature of the present invention.

Between the abutment surfaces on the retaining pieces and on the part A of the insulator a yielding insertion F of leather, lead, 75 paper treated with asphalt or the like may be provided in a known manner.

As is seen from Figure 2 the retaining pieces D may for example constitute a ring 80 in three parts.

The present invention may be applied to double-cap insulators as well as to insulators provided with a cap and bolt.

What I claim is:—

1. A suspension insulator comprising an insulating body having an outwardly inclined abutment surface and a unitary cap placed over said body and extending over said inclined surface, wedge shaped holding pieces inserted between said cap and said insulating body, said wedge shaped pieces lying on said inclined abutment surface, registering circumferential grooves on the inside surface of the cap and the outer surface of the holding pieces, and flexible members in said grooves. 85 90 95

2. A suspension insulator comprising an insulating body having an outwardly inclined abutment surface and a cap placed over said body and extending over said inclined surface, a wedge shaped holding ring inserted 100 between said cap and said insulating body, said wedge shaped ring lying on said inclined abutment surface, registering circumferential grooves on the inside surface of the cap and the outer surface of the holding ring, and 105 flexible members in said grooves.

3. A suspension insulator comprising an insulator body having an outwardly inclined

abutment surface and a unitary cap placed over said body and extending over said inclined surface, wedge shaped holding pieces inserted between said cap and said insulating body, said wedge shaped pieces lying on said inclined abutment surface, registering circumferential grooves on the inside surface of

the cap and the outer surface of the holding pieces, flexible members in said grooves, and cushioning means disposed between said inclined abutment surface and said wedge shaped pieces. 10

OTTO BECKER.
